CLAIM

The ornamental design for a combined powered scrubber, polisher and associated storage and recharger housing, as shown and described.

DESCRIPTION

FIG. 1 is an exploded front elevational view of a combined powered scrubber, polisher and associated storage and recharger housing showing our new design;

FIG. 2 is an exploded rear elevational view thereof;

FIG. 3 is an exploded right side elevational view thereof;

FIG. 4 is an exploded left side elevational view thereof;

FIG. 5 is an exploded top plan view thereof; and,

FIG. 6 is an exploded bottom plan view thereof.
